UNITED STATES PATENT OFFICE

JOHN H. VICKERS, OF HUDSON, NEW YORK, ASSIGNOR TO DAVID S. BAKER, OF GREENWICH, CONNECTICUT

APPARATUS FOR HANDLING MATERIALS

Application filed June 29, 1927. Serial No. 202,197.

This invention relates to apparatus for handling materials, and aims to facilitate the movement, and more particularly the treatment, of materials.

5 The invention relates to apparatus of the type described and claimed in the co-pending application of David S. Baker, filed June 27, 1923, Serial No. 647,964, in which a number of collapsible carriers, each provided with 10 a number of carrying elements are moved in such manner as to place the carrying elements in edge-to-edge relation at the loading station, and then in superimposed relation in a treatment space; and more particularly 15 to an improved apparatus of the same type described in the co-pending application of David S. Baker and Bjornulf Johnsen, filed March 24, 1927, Serial No. 177,867, in which the carriers are inclined, so as to place their 20 carrying elements in stepped relation in the treatment space, and are moved outwardly along one set of tracks and inwardly along another set of tracks located either above or below the first set.

25 The present invention aims to improve, simplify, and increase the capacity of the handling apparatus shown in the aforesaid applications, and more particularly to provide a simple and convenient apparatus for 30 transferring collapsible carriers from one set of tracks to another without changing the relative position of the carrying elements of each carrier, and to maintain such carrying elements in stepped relation during the transfer; and to provide means for positively 35 controlling the movement of each of a number of such carriers throughout a closed circuit.

Other objects and advantages of the invention are hereinafter described in connection 40 with a detailed description of a practical apparatus embodying the invention and shown in the accompanying drawings, in which:—

45 Figs. 1A, 1B and 1C are the front, middle and rear parts of a partly diagrammatic side elevation of the entire apparatus;

Fig. 2 is an enlarged side elevation of the dumping and loading part of the apparatus with the tracks nearest the observer removed;

50 Fig. 3 is an enlarged side elevation of the rear end of the apparatus showing the ele-

vator sectioned on the central longitudinal plane of the apparatus;

Figs. 4 and 5 are detailed views of one of the chain casings for holding down a part of the load conveyer; Fig. 4 being a side elevation of the casing; and Fig. 5 an end view; 55

Fig. 6 is a transverse sectional elevation of the apparatus taken on the line 6—6 of Fig. 1A;

Fig. 7 is a plan view showing a carrier in 60 loading position and the rails supporting it;

Fig. 8 is a transverse section on the line 8—8 of Fig. 7; and

Figs. 9, 10 and 11, on sheet 5, are detailed 65 views of the mechanism for controlling the movement of the elevator; Fig. 9 being a side elevation of one of the cams and hooks of the elevator stopping mechanism, the shafts being sectioned on the line 9—9 of Fig. 10; Fig. 10 being a broken horizontal section on 70 the line 10—10 of Fig. 1C; and Fig. 11 a side view of the gears operating the drive for the elevator. 70

The apparatus illustrated includes a large 75 number of collapsible carriers 10, each provided with a plurality of carrying elements such as trays 20, and means for moving these carriers in a closed circuit which takes each tray past a loading station L, through a treatment space T, to a dumping station D, 80 and back to the loading station.

The construction of a carrier 10 is best 85 shown in Figs. 3, 6, 7 and 8. The carrier has a rear connecting member 11 consisting of rigid side bars 12 joined by tie rods 13 and a front connecting member 14 which is similar except that its side bars 15 are slightly closer together than those of the rear connecting member. A number of trays 20 are mounted on the connecting members 11, 14. Each tray 90 has on its bottom two spaced cross bars 21 having depending tabs 22 near their front ends. The tabs 22 are pivoted on the tie rods 16 of the front connecting member 14 while the rear ends of the cross bars 21 are pivoted 95 on the tie rods 13 of the rear connecting member 11. The distance between the adjacent tie rods of each connecting member is equal to the length l of one of the trays 20 so that the trays may be brought into edge-to-edge re- 100

lation in a common plane by bringing the front and rear connecting members together as shown in Figs. 7 and 8. In this position, one edge of the side bars 15 of the front connecting member comes in contact with the tie rods 13 of the rear connecting member as shown in Fig. 8. By spreading the connecting members apart, the trays 20 may be brought into superimposed relation. The connecting members serve to keep the trays parallel in all positions thereof. Supporting members 30 are hinged to the upper tie rods 13a, 16a of the rear and front connecting members outside the side bars of the connecting members. The supporting members like the cross bars 21 have depending tabs 32 which are pivoted on the upper tie rod 16a so that the supporting members are always parallel to all the cross pieces 21 and to the trays. Each supporting member is provided with two flanged wheels of which the rear-most 33 faces outwardly while the front one 34 faces inwardly. Projecting along the axes of the front wheels 34 are fingers 35 each provided with two grooves 36, 37. At the ends of the lowest tie rod 16b of the front connecting member are a pair of outwardly facing flanged wheels 38 which lie wholly inside the supporting surfaces of the wheels 33.

It should be noted that whenever the two upper pairs of wheels 33, 34 are supported on the same horizontal track, each tray of the carrier will be horizontal, and that when the lower wheels 38 are supported on a track slightly below that supporting the upper wheels, the trays will be in edge-to-edge relation in a common horizontal plane, while when the lower wheels are supported on a track substantially below the level of that which supports the upper wheels, the trays will be in superimposed relation.

Tracks are provided for supporting and guiding the carriers by engagement with their wheels. There is an upper track 40 for the upper wheels 33, 34, and a lower track 50 of slightly narrower gauge for the lower wheels 38.

The arrangement of the tracks 40, 50 may best be seen in Figs. 1A, 1B, 1C. The tracks have horizontal portions 41, 51 extending under the loading station L in substantially the same horizontal plane. In the upper part of the treatment space T, the tracks have horizontal portions 42, 52 which are spaced apart in a vertical direction by a distance less than the length of the connecting members of the carriers. The loading portion 51 and the upper treatment portion 52 of the track 50 are connected by a downwardly inclined portion 53. In the lower portion of the treatment space T, the tracks have spaced horizontal portions 44, 54. Horizontal extensions 45, 55 of the portions 44, 54 extend across the dumping station D. Just

behind the dumping station D, the tracks have vertical portions 46, 56 lying in substantially the same plane. The portion 46 starts just above the junction of the portions 44 and 45 of the track 40 and extends upward to the point 47 above the loading portion 41 of this track. The vertical portion 56 of the track 50 extends from just above the junction of the horizontal portions 54, 55 of this track to a point 57 below the point 47, with a short interruption at 58 just above a junction of the horizontal portions 44, 45 of the track 40. A downwardly inclined portion 49 connects the upper end of the vertical portion 46 of the track 40 with the front end of its loading portion 41 while an upwardly inclined portion 59 connects the upper end of the vertical portion 56 of the track 50 with the front end of its loading portion 51.

Automatic movement of the carriers 10 along the tracks is secured by conveyers positively connected to a common driving means so that they operate in timed relation to each other. Each conveyer consists of two chains having reaches lying close to a portion of one of the tracks and provided with flights for engaging a part of each carrier 10. One of the conveyers is an elevator for moving the carriers from the ends of the portions 42, 52 of the tracks to the ends of the portions 44, 54. Two pairs of kickers move the carriers on and off the elevator respectively.

The moving means will be described in the order in which they operate upon a carrier in its circuit through the apparatus. A load conveyer 60, consisting of a pair of chains passing over sprockets 61, 62 and provided with flights 63 which engage the outer grooves 36 of the fingers 35 of the carriers, draws each carrier past the loading station L and into the upper portion of the treatment space T. To prevent the carriers from running forward under the influence of gravity as their lower wheels descend the inclined track 53, the flights 63 of the load conveyer 60 are made double, and each consists of a part 63a which lies in front of one of the fingers 35, and a part 63b which lies behind this finger. To prevent the upper ends of the carriers from leaving the upper track 40 when the lower wheels of the carrier descend the inclined portion 53 of the lower track, the rear part 63b of the flights 63 is hooked so that each of them extends over the finger 35 which it engages, and chain covers 60c are provided to hold down the portions of the chains of the conveyer 60 located just beyond the inclined portion 53 of the lower track. One of these chain covers 60c is shown diagrammatically in Fig. 1B and in detail in Figs. 4 and 5. The chain cover 60c completely encloses a portion of one of the chains of the conveyer.

60 but is provided with a longitudinal slot 60d in its upper surface through which the flight members 63a and 63b project to engage the fingers 35. An upper treatment 5 conveyor 70, consisting of a pair of chains passing over sprockets 71, 72 and provided with flights 73 which engage the inner grooves 37 of the fingers 35 of each carrier, draws the carriers through the upper portion 10 of the treatment space. The upper kicker 80, consisting of a pair of arms 81 positioned to engage the outer grooves 36 of the fingers 35 of each carrier, moves the carriers from the portions 42, 52 of the tracks 15 40, 50 onto the elevator 90. The elevator 90 consists of a pair of chains passing over sprockets 91, 92 and provided with horizontal track segments 93, 94 which carry the upper and lower wheels 33, 34, 38 of each carrier 20 as it is pushed off the end of the portions 42, 52 of the tracks, and lower the carrier until its wheels are on a level with the ends of the portions 44, 54 of the tracks. Each of the track segments 93, 94 is secured 25 to pivots at the two ends of one of the links of one of the chains of the elevator. These pivots consists of cross bars 90a extending from one chain to the other. Each track section is provided with a leg 93a which rests 30 on the next pivot of one of the chains below the cross bars 90a, but is not attached to this pivot. The upper reaches of the elevator chains are supported on bars 95. This arrangement insures maintaining horizontal 35 those of the track sections 93, 94 which are on the descending reaches of the chains. At the same time, the fact that the legs 93a of the track sections are not connected to the chain pivots on which they rest leaves the 40 links of the chains free to pass around the sprockets 91, 92, as clearly shown in Fig. 1C. The lower kicker 100 consists of two arms 101, positioned to engage the outer grooves 36 of the fingers 35 of each carrier 45 and to move the carrier from the track segments of the elevator onto the ends of the portions 44, 54 of the track. A lower treatment conveyor 110, consisting of chains passing over sprockets 111, 112 and provided with 50 flights 113 which engage the lowest tie rod 16a of the rear connecting member 14 of each carrier near its outer ends (see Fig. 6), moves the carriers through the lower portion of the treatment space T. A dump spacing conveyor 120, consisting of two chains passing over sprockets 121 and sprockets 122, which are co-axial with and of the same size as the sprockets 112, and provided with a pair of flights 123 which engage the tie rod 16b of 55 each carrier at a distance from its ends, draws the carriers across the dumping station D. A dump elevating conveyor 130, consisting of two chains passing around sprockets 131, 132, over sprockets 133, 134, 60 and under sprockets 135, and provided with

double flights 136 which engage the inner grooves 37 of the fingers 35 of each carrier, moves the carriers vertically upward at the dumping station and then back to the loading station. The sprockets 134 have a recess 70 138 for the flights 136 (Fig. 2). The flights 136 of the conveyor 130 are made double, like those of the load conveyor 60, to prevent the carriers from running ahead by gravity when their upper wheels pass down the 75 inclined portion 49 of the track.

The speed of the conveyers is so related that the trays move past the loading station closely spaced in single file, and through the treatment space closely spaced in multiple 80 file, while the carriers are spaced apart at the dumping station. In order that each carrier may be positively guided and timed throughout its circuit, and, for this purpose may always be in engagement with one or another of the conveyers, the flights of the different conveyers are spaced apart by distances proportional to the rates of movement of the conveyers. Thus taking the length l of a tray as the linear unit and 90 the number of trays in each carrier as n , the rate of movement of the load conveyor 60 is n linear units per unit of time and its flights 63 are n linear units apart; the rate of movement of the treatment conveyers 95 70 and 110 is one linear unit per unit of time, and the flights of these conveyers are spaced one linear unit apart; while the rate of movement of the dump conveyers 120 and 130 is greater than n linear units per unit 100 of time. In the form shown, the number of trays in each carrier is seven, and the rate of movement of the dump conveyers 120, 130 is sixteen linear units per unit of time and the flights of these conveyers are sixteen 105 linear units apart. In this connection, it should be noted that as the load spacing conveyor 120 has only one pair of flights, the length of the chains of this conveyor is sixteen linear units. The kickers 80 and 100 110 rotate at the rate of one revolution in one time unit, that is to say, they each make one revolution while the treatment conveyers are moving through a distance of one linear unit. They rotate in the same direction one half 115 cycle apart. The elevator 90 has an intermittent movement, being held stationary during the lower part of the revolution of the upper kicker 80 and the upper part of the revolution of the lower kicker 100, and moving through a distance equal to the length of the connecting members of the carriers during the upper part of the revolution of the upper kicker 80. 120

Various forms of known mechanism may 125 be used to move the conveyers at the proper relative rates above specified. Mechanism suitable for this purpose is shown in the drawings and consists of well-known mechanical elements connecting a main driving 130

shaft 140 with each of the conveyers and with the kickers. Special mechanism for giving the elevator an intermittent movement is hereinafter described.

- 5 The mechanism for driving the conveyers is clearly shown diagrammatically in Figs. 1A, 1B, 1C, and as all the parts of this mechanism are well-known mechanical elements, it will be sufficient to list the parts driving 10 each conveyer. The load conveyer 60 is driven from the shaft 140 through the following parts: worm 65, gear 66, sprocket 67, chain 68, sprocket 69, sprocket 62. The drive of the upper treatment conveyer 70 includes 15 the following parts: shaft 140, worm 75, gear 76, sprocket 77, chain 78, sprocket 79, sprocket 72. The drive of the upper kicker 80 includes: shaft 140, worm 75, gear 76, sprocket 85, chain 86, sprocket 87. The connection 20 between the shaft 140 and the elevator 90 includes: worm 75, gear 76, intermittent mechanism 195 (hereinafter described), sprocket 96, chain 97, sprocket 98, sprocket 91. The drive of the lower kicker 100 includes: shaft 140, worm 115, gear 25 116, sprocket 117, chains 118 (with intermediate sprockets 118'), sprocket 119, sprocket 112. The drive of the dump elevator conveyer 130 includes: shaft 140, worm 115, gear 116, sprocket 137, chain 138, sprocket 139, and 30 sprocket 132. The dump spacing conveyer 120 is driven from the dump elevator conveyer 130 through: sprocket 131, sprocket 125 (fixed on same shaft), chain 126, sprocket 127, sprocket 121.
- 35 40 The intermittent mechanism 195 connecting the gear 76 and the sprocket 96, which, in connection with the stopping mechanism controls the movement of the elevator 90, is shown in Fig. 11. It consists of a gear 141 fixed on the same shaft as the sprocket 76, a gear 142 fixed on the same shaft as the sprocket 96, and an intermediate gear 143. As the sprockets 85 and 87 are the same size, the gear 141 rotates in unison with the upper kicker 80.
- 45 50 The gear 141 has a toothed portion 141a which engages the gear 143 and through it controls the movement of the elevator during a little more than one-half of each revolution of the gear 141, and a blank portion 141b which passes over the teeth of the gear 143 to permit the elevator to remain at rest during the remainder of each revolution of the gear 141. The blank portion 141b of the gear 141 is adjacent to the gear 143 during the lower part 55 60 of each revolution of the upper kicker 80 and the upper part of each revolution of the lower kicker 100. Stopping mechanism is provided to hold the elevator stationary while the blank portion 141b of the gear 141 is opposite the gear 143 so as to permit

the upper kicker 80 to move a carrier upon the elevator and the lower kicker 100 to move a carrier off the elevator during this part of the operation. The stopping mechanism shown in Figs. 1C, 9 and 10 includes a pair of hooked levers 144 journalled on a short shaft 145 located between the two reaches of the elevator, so that the hooks 146 of the levers may engage the cross bars 90a of the elevator. The rear ends of the levers 144 are provided with cam followers 147 engaging grooves in cams 148. The cams are mounted on a cross shaft 149 located between the reaches of the elevator chains, and rotated in synchronism with the gear 141 and the kickers 80 and 100 by a chain connection 149a with the shaft of the lower kicker 100. The grooves in the cams 148 are formed so as to bring the hooks 146 into the path of the cross bars 90a on the upper reach of the chain when the blank portion 141b is opposite the gear 143 and so as to tip the hooks below the path of these cross bars while the toothed portion 141a of the gear 141 is in engagement with the gear 143.

55 60 During the periods in which the elevator is not held stationary by the lock bar, the engagement between the toothed portion 141a of the gear 141 and the gear 143 serves as a positive driving means for the elevator.

65 70 Various means for supporting the tracks and working parts shown in Figs. 1A, 1B, and 1C, can readily be arranged by any competent builder, and the particular form of such supporting means is not a vital feature of the present invention. A practical means 75 for supporting the tracks and working parts is however indicated in Fig. 6. A supporting frame shown consists of two vertical side frames 150 which may be stiffened by cross pieces 151, 152, positioned so as not to interfere with the movement of the carriers. The tracks 40, 50 may be supported on brackets 153 extending inwardly from the side frames. If desired, the lowest portions 54, 55 on the lower track 50, may be supported on shoes 154, mounted on the cross pieces 152, instead of on brackets. The various sprockets for the driving chains and conveyer chains may be mounted on shafts 155 extending between the side frames and journalled therein. To 80 avoid twisting strains on these shafts, the driving chains and their sprockets, as well as the conveyer chains and sprockets, may be arranged in pairs as shown in Fig. 6. Supports may be provided under the long reaches of the conveyer chains to prevent them from sagging, particularly where the chains are so positioned that they would strike something, if they sagged. Thus as 85 shown in Fig. 6, supports 156, 157 may be provided to prevent the upper and lower reaches of the chains of the lower treatment conveyer 110 from striking the cross pieces 152 and the floor 158 of the apparatus.

90 95 The apparatus which should be used for 130

loading the trays at the loading station L depends upon the nature of the material to be treated. If this material is of a somewhat viscous nature, the loading apparatus 5 may include a chute L1, a roller L2 at the bottom of the chute, a scraper L3 to scrape material from the roller and direct it into the trays, and a leveler L4 whose lower edge L5 is close to the top of the loaded trays, 10 and serves to level off the material therein. The apparatus for receiving the material at the dumping station D may consist of a hopper D1 at the bottom of which is a screw conveyor D2.

15 For certain treatments of the material such as drying, it is desirable to have the treatment space T enclosed. This may be done by a sheathing 160 having sides 161 covering the side frames 150, an end wall 162 just beyond 20 the dumping station D, a horizontal wall 163 extending from the end wall 162 over the sections 45, 44 of the track 40, an end wall 164 extending upward from the horizontal wall 163 just behind the loading station L, 25 and just in front of the inclined section 53 of the track 50, a top wall 165 extending from the wall 164 to the rear end of the apparatus just above the section 42 of the track 40, and an inclined wall 166 under the elevator 90. The entrance opening 167 of the 30 chamber is formed in the wall 164 where the tracks 40 and 50 are in substantially the same plane, and the height of this opening is approximately that of one tray. The upper 35 edge of the entrance opening 167 may serve as the leveler L4. The outlet opening 168 is formed in the wall 163, just in front of the vertical portions 56 and 46 of the tracks, where these portions are in substantially the 40 same plane. The width of this opening is approximately the same as the height of the entrance opening. The only other openings required in the sheathing are the small openings necessary for the passage of the various 45 shafts, and the conveyer 70, and an opening for the passage of the screw conveyer D2. Thus, notwithstanding the continuous operation of the apparatus, the treatment space may be so completely enclosed that the 50 atmospheric conditions desired for the treatment of the material may easily be maintained therein.

The operation of the device described is as follows:

55 A number of carriers 10 equal to the number of pairs of flights on the active reaches of the conveyers are used in the apparatus. The main driving shaft 140 is driven from any convenient source of power, such as an 60 electric motor 170, as shown in Fig. 1B and the roller L2 of the loading device and the worm at the dumping station are also continuously power-driven. The carriers are brought in succession from the dumping station 65 by the dump elevating conveyer 130,

which releases them just as their upper wheels drop over a jog 171 in the track 40, just in front of the loading device. As the carriers reach this position, they are picked up successively by the loading conveyer 60 whose flights are so spaced that the front edge of the front tray of each carrier follows closely behind the rear edge of the rear tray of the preceding carrier (see Fig. 2). As the carriers pass under the loading device therefore, their trays form a continuous traveling support upon which material may be continuously discharged from the scraper L3 and upon which it may be level by the leveler L4. Each carrier enters the treatment space 70 through the opening 167 with its trays in edge-to-edge relation in a common plane, but as soon as the lower wheels 38 of the carrier reach the inclined portion 53 of the track 50, their connecting members 11, 14 separate, 75 placing their trays in stepped superimposed relation. By the time each carrier is in this condition, its upper wheels have been pushed up a jog 172 in the track 40 and released by the loading conveyer 60. In this position, 80 each carrier is picked up by a flight of the conveyer 70, and moved forward with the front edge of each of its trays close to the rear edge of the corresponding tray of the preceding carrier, so that, in the upper portion of the treatment space, the trays form a set of superimposed continuous traveling supports which are closely spaced but separated by a distance sufficient to permit the circulation of air or other gas between them 85 for the treatment of the material. As each carrier approaches the end of the portions 42, 52 of the tracks, it is moved rapidly onto the track segments 93, 94 of the elevator 90, 90 by the kicker 80. With its wheels supported 95 on these track segments, it descends rapidly in a direction parallel to its connecting members, so that the trays move in single file, until the track segments are in alignment 100 with the ends of the tracks 44, 54. It is then 105 pushed onto the ends of these tracks by the kicker 100, and its wheels slide over jogs 173 in these tracks leaving it in a position where it is picked up by the lower treatment conveyer 110. In the lower part of the treatment space, the carriers move in the opposite direction from that in which they moved in the upper part of the space. In the lower 110 part of the space, also, the trays of the carriers form a set of continuous traveling supports located in closely spaced horizontal planes. As the lower wheels 38 of each carrier arrive directly over the axis of the sprockets 112, 122, the carrier is engaged by the single pair of pickers 123 of the spacing conveyer 120, and moved forward rapidly 115 across the hopper D1 at the dumping station. On being released by these pickers, it is stopped by engagement of its lower wheels 38 with bumpers 174 near the ends of the 120

horizontal portions 55 of the track 50. This brings its upper wheels in front of the vertical portions 46, 56 of the tracks. As soon as the carrier reaches this position, its fingers 35 are engaged by a pair of pickers of the dump elevating conveyer 130, which raise its front upper wheels 34 vertically along the vertical portion 46 of the track 40. As soon as this movement has lifted its rear upper wheels 33 clear of the portion 45 of the track 40, its rear connecting member 11 is no longer supported and falls against its front connecting member 14, bringing its trays edge-to-edge in the inclined plane of the connecting members, so that part of the material contained in the trays is dumped into the hopper D1. As the upward movement of the front upper wheels 34 of the carrier continues, its lower wheels 38 roll back along the horizontal portion 55 of the track 50 inclining the common plane of the trays more and more steeply, and dumping more and more of the material from the trays into the hopper. When the wheels 34 of the carrier have been raised to a distance above the horizontal portion 55 of the track 50 equal to the length of the connecting members of the carrier, the connecting members and the trays hang vertically, and the last of the material on the trays falls into the hopper. The movement of the dump elevating conveyer 130 is so rapid that as the connecting members of the carrier approach a vertical position, they swing backward coming against a cross piece 56a between the track sections 56 with a decided bump which has the effect of shaking out any material which may tend to adhere to the trays. The entire carrier is then drawn vertically upward with its wheels 33 as well as its wheels 34 in engagement with the vertical portion 46 of the track 40, and its lower wheels 38 in engagement with the vertical portion 56 of the track 50 (see Fig. 2). The backward movement of the lower end of the carrier takes place while the pickers 123 of the conveyer 120 are returning along the lower reach of this conveyer, and by the time these pickers engage and draw forward the next carrier, the preceding carrier has been raised sufficiently to bring its lower end above the portion 45 of the track 40. After each carrier has been raised along the vertical portions 46, 56 of the tracks, the carrier is returned to its initial position by the conveyer 130. The connecting portions 49, 59 of the tracks along which the carrier passes in this movement turn from a vertical into a common horizontal plane, so that the trays of the carrier are brought from edge-to-edge relation in a vertical plane to edge-to-edge relation in a horizontal plane. The speed of the conveyer 130 is so much greater than that of the conveyer 120 that the front end of each carrier is brought to the jog 171 in the track 40 by the

conveyer 130, just as the rear end of the preceding carrier, which is being moved by the conveyer 60, reaches this point. Thus the carriers, after being spaced apart during their engagement with the dump conveyers 120 and 130, are brought again into closely spaced relation at the loading station. 70

What is claimed is:

1. In apparatus for handling materials, the combination of upper and lower tracks, a plurality of carriers, means for moving carriers slowly in closely spaced relation along the upper track towards the end thereof, means for moving carriers slowly in closely spaced relation along the lower track away 75 from the end thereof, an elevator extending across the ends of the tracks and having track sections, means for moving the elevator intermittently so that it comes to rest when two of its track sections are in alignment with the two tracks, means for moving the foremost carrier on one track away from the following carriers and onto a track section of the elevator, and means for simultaneously moving a carrier from another track section of the elevator onto the other track and placing it close behind the rearmost carrier on that track. 80

2. In apparatus for handling materials, the combination of an upper track and a lower track, a plurality of carriers, means for moving the carriers in closely spaced relation along the upper track toward the end thereof, means for moving the carriers in closely spaced relation along the lower track away 95 from the end thereof, a descending elevator extending across the ends of the tracks and having track sections, means for intermittently locking the elevator when two of its track sections are in alignment with the two tracks, and means operative simultaneously 100 to move the foremost carrier on the upper track away from the following carrier and onto a track section of the elevator and to move a carrier from another track section 105 of the elevator onto the lower track and against the rearmost carrier on said track. 110

3. In apparatus for handling materials, the combination with an upper and a lower track and carriers having wheels running on said tracks, of an elevator adjacent to one end of both tracks and comprising track sections, and means for moving said track sections from alignment with one track to alignment with the other track. 115

4. In apparatus for handling materials, the combination of an upper and a lower track, collapsible carriers each having two wheels adapted to engage one of the tracks, an elevator extending across the ends of the tracks and having track sections of a length sufficient to support the two wheels of each carrier, and means for moving said track sections from alignment with one upper track to alignment with the other track. 120

5. In apparatus for handling materials,

the combination with an upper pair of superimposed rails and a lower pair of superimposed rails and a plurality of carriers each comprising a rigid supporting member having two spaced wheels running on one of the rails to maintain it parallel to said rail, two rigid connecting members hinged to said supporting member, a wheel on one of the connecting members engaging the other rail and separated by the first mentioned rail by a distance greater than the distance between the rails so that said connecting member is inclined to the rails and carrying elements hinged to said connecting member in parallelogram arrangement, of an elevator having track sections positioned to receive the upper and lower wheels of each carrier from the upper pair of rails, and means for moving said track sections into alignment with the lower pair of rails.

6. In apparatus for handling materials, the combination with an upper set of tracks and a lower set of tracks and a plurality of carriers each having horizontal carrying elements and an inclined connecting member having wheels engaging both the tracks of one set, of an elevator comprising a conveyor extending across the ends of both sets of tracks in a direction parallel to the connecting members of the carriers, and horizontal track sections secured to said conveyor.

7. In apparatus for handling materials, the combination with a plurality of carriers each having two connecting members and carrying elements hinged to them in parallelogram arrangement and an upper set of tracks and a lower set of tracks each adapted to support the carriers with their carrying elements horizontal and their connecting members inclined, of an elevator comprising a conveyor extending across the ends of the tracks and parallel to the connecting members of the carriers, and horizontal track sections carried by said conveyor and lying in horizontal planes separated by the same distance which separates the upper and lower tracks of each set of tracks.

8. Apparatus for handling materials, comprising a plurality of carriers each having a connecting member and a number of parallel carrying elements inclined to the connecting member and held in stepped relation thereby, means for moving said carriers successively in a direction parallel to their connecting members at a relatively high speed and then in a direction parallel to their carrying elements at a relatively low speed.

9. Apparatus for handling materials, comprising a plurality of carriers each having two connecting members and carrying elements hinged thereto in parallelogram arrangement, means for moving each carrier first horizontally and then in a direction at an acute angle to the horizontal, and means for maintaining the carrying elements of each

carrier horizontal and the connecting members of each carrier parallel to the direction of the second movement, throughout both movements.

10. Apparatus for handling materials, comprising a plurality of carriers, means for guiding the carriers in a closed circuit, and means for positively moving each carrier throughout the circuit, comprising a plurality of moving means interconnected independently of the carriers and moving at different rates of speed and each having engaging means spaced in proportion to its rate of movement and positioned to engage a carrier when released by the preceding moving means.

11. Apparatus for handling materials, comprising a plurality of carriers, means for guiding the carriers in a closed circuit, means for positively moving each carrier throughout the circuit and for spacing the carriers differently in different parts of the circuit, comprising a common driving means, and conveyors driven therefrom at different rates of speed and each provided with flights spaced in proportion to its speed and positioned to engage each carrier as it is released by a flight of the preceding conveyor.

12. In apparatus for handling materials, a plurality of carriers having carrying elements, a conveyor adapted to move the carriers slowly in closely spaced relation through a treatment space, a rapidly moving conveyor adapted to engage each carrier as it reaches the end of the treatment space and to move it forward to a dumping station, a second rapidly moving conveyor adapted to engage each carrier at the dumping station and to move it toward a loading station and to release it, and a conveyor adapted to engage each carrier just as it is released by the second rapidly moving conveyor and to move it forward past the loading station at such a rate that its rear end is just in front of the front end of the following carrier released by the second rapidly moving conveyor.

13. In apparatus for handling materials, the combination with a carrier having wheels at each of its ends, of two tracks having separated ends and converging until they lie substantially in the same horizontal plane, and a continuous conveyor positioned to engage the carrier and raise it vertically until its upper and lower wheels are at the ends of said two tracks respectively and then to move it along the tracks with its upper and lower wheels supported thereon, so that it is brought into a horizontal position.

14. In apparatus for handling materials, the combination with a carrier having pairs of wheels of different gauges at its opposite ends, of a track of one gauge having a vertical portion connected by a continuous curve to a downwardly inclined portion and a horizontal portion beyond the inclined portion,

a track of the other gauge having a vertical portion substantially co-planer with the vertical portion of the first track, a horizontal portion substantially co-planer with the horizontal portion of the first track and an inclined portion connecting the vertical and horizontal portions, and a continuous conveyer adapted to engage the carrier and move its upper wheels along the first track from the vertical portion thereof to the horizontal portion thereof while the lower wheels of the carrier are supported by the second track, so that the carrier is brought from a vertical position to a horizontal position during such movement.

15. Apparatus for handling materials, comprising a plurality of carriers each having carrying elements which may be placed in edge-to-edge and in superimposed relation, two tracks located one above the other, means for moving the carriers outwardly along one track, transferring them to the other track, moving them inwardly along said other track and transferring them back to the first track, so that they move in a closed circuit, means for tipping up the carrying elements of each carrier as it is transferred from the lower track to the upper track to dump material from the carrying elements, means for placing the carrying elements of each carrier in a common horizontal plane as they reach the upper track, means for changing the carrying elements of each carrier from edge-to-edge relation in the common plane to superimposed relation in spaced horizontal planes as the carrier is moved along the upper track, and means for retaining the carrying elements of each carrier in such superimposed relation during its transfer to the lower track and its movement along the lower track.

16. In apparatus for handling materials, an elevator comprising an inclined chain conveyer and horizontal track sections each secured to both ends of one link of the conveyor, and a leg on each track section resting on another link of the conveyer.

17. In apparatus for handling materials, an elevator comprising a non-horizontal chain conveyor, and horizontal supports each secured to both ends of one link of the conveyor and each having a rigid projection resting against another link of the conveyor.

18. In apparatus for handling materials, an elevator comprising a pair of inclined conveyor chains, a pair of cross-rods connecting both ends of a pair of corresponding links of the two chains, horizontal track sections each secured to one end of both the said cross-rods, and a leg on each track section resting on a link of one of the chains behind said cross-rods.

19. In apparatus for handling materials, an elevator comprising a pair of inclined conveyer chains, a pair of cross-rods connect-

ing both ends of a pair of corresponding links of the two chains, and horizontal track sections each secured to one end of both of said cross-rods.

20. In apparatus for handling materials, an elevator for transferring carriers from vertically separated tracks, comprising a pair of conveyer chains and cross-rods extending between said chains, driving means for moving said conveyer intermittently, a stop for the conveyer, and means for moving said stop into the path of said cross-rods when the driving means permit the stopping of the elevator.

21. In apparatus for handling materials, comprising a plurality of carriers, means for guiding the carriers in a closed circuit lying in a vertical plane, means for positively moving each carrier throughout the circuit and for spacing the carriers differently in different parts of the circuit, comprising a common driving means, and conveyers driven therefrom at different rates of speed and each provided with flights spaced in proportion to its speed and positioned to engage each carrier as it is released by the flights of the preceding carrier, the flights of the conveyers which engage the carriers in the descending parts of the circuit being formed to prevent the carriers from moving forward under gravity in advance of the conveyer movement.

22. In apparatus for handling materials, the combination with a carrier having connecting members and carrying elements hinged to them in parallelogram arrangement and wheels at both ends of the connecting members, of a horizontal track for the upper wheels and an inclined track for the lower wheels, means for moving the carrier along the tracks so that its lower wheels descend along the inclined track, and positive means for preventing the upper wheels from rising from the upper tracks during the descent of the lower wheels.

23. In apparatus for handling materials, the combination with a carrier having connecting members and carrying elements hinged to them in parallelogram arrangement and wheels at its upper and lower ends and a projecting finger near its upper end, of a horizontal track for the upper wheels, a downwardly inclined track for the lower wheels, a conveyer chain, a hook on said conveyer chain adapted to engage and extend over the finger of the carrier, and a plate above the conveyer chain preventing upward movement of the chain and its hook and containing a slot for the passage of the hook.

24. In apparatus for handling materials, the combination with a carrier having connecting members and carrying elements hinged together in parallelogram arrangement, of means for moving the carrier with

the lower ends of its connecting members inclined forward and with its carrying elements horizontal, hoisting means for raising the rear connecting member of the carrier vertically so that the lower ends of its connecting members swing backward and its carrying elements are turned into a vertical position, and means for suddenly arresting the backward swing of the carrier to jar material from its carrying elements.

25. In apparatus for handling materials, the combination with a carrier having two connecting members and carrying elements hinged to said connecting members in parallelogram arrangement and wheels at the upper ends of both connecting members and at the lower end of one of them, of upper and lower horizontal tracks for supporting the upper and lower wheels of the carrier separated by a distance less than the length of the carrier, means for advancing the carrier along said tracks with the lower ends of its connecting members inclined forward, raising means adapted to engage the carrier and move its rear upper wheel upwardly so rapidly that its lower wheels leave the lower horizontal track before the carrier swings to a vertical position, and means for suddenly arresting the swinging of the carrier when it reaches the vertical position to jar material from its carrying elements.

26. In apparatus for handling materials, the combination with a carrier having two connecting members and carrying elements hinged to them in parallelogram arrangement and wheels at the upper ends of both connecting members and at the lower end of one of them, of upper and lower horizontal tracks for supporting the upper and lower wheels of the carrier separated by a distance less than the length of the carrier, means for advancing the carrier along said tracks with the lower ends of its connecting members inclined forward, two vertical tracks lying in a common plane, and raising means adapted to engage the carrier when its upper end has just passed said vertical tracks and to move its rear upper wheel upwardly along one of the vertical tracks so that its rear lower wheel moves rearwardly along the lower horizontal track and then upwardly along one of the vertical tracks.

27. In apparatus for handling materials, an elevator comprising an inclined chain conveyer, horizontal track sections each secured to a single link of the conveyer and running perpendicular to the axis of rotation of the conveyer, wheeled carriers each having connected carrying elements, and means to move said carriers onto and off said track sections.

28. Apparatus for handling materials, comprising a plurality of collapsible carriers each having two connecting members and carrying elements hinged thereto in parallelogram arrangement, means for moving the car-

riers horizontally at an upper level in one direction and horizontally in the opposite direction at a lower level, means for causing a collapsing and re-opening of each carrier during one of said horizontal movements, means for transferring each carrier from one level to the other and maintaining its carrying elements horizontal during such transfer, and means for preventing a collapsing of each carrier during such transfer.

In testimony whereof I have hereunto set my hand.

JOHN H. VICKERS.
